UNITED STATES PATENT OFFICE.

GEORGE HOFMANN AND ROBERT G. SCHROEDER, OF CHICAGO, ILLINOIS, ASSIGNEES
TO RALPH BARD, TRUSTEE, OF CHICAGO, ILLINOIS.

CAP STRUCTURE FOR WRITING INSTRUMENTS.

Original application filed February 2, 1922, Serial No. 533,676. Divided and this application filed
February 8, 1923. Serial No. 617,698.

To all whom it may concern:

Be it known that we, GEORGE HOFMANN and ROBERT G. SCHROEDER, citizens of the United States, residing at Chicago, in the county of Cook and State of Illinois, have made certain new and useful Improvements in Cap Structures for Writing Instruments, of which the following is a specification.

Our invention has for its general object 10 to provide a simple, compact and desirable cap-structure particularly designed for use in connection with a combined fountain pen and lead-feeding pencil, such as the combined instrument shown in our pending application for Letters Patent of the United States Serial No. 533,676, filed February 2, 1922, of which application this is a division.

In the cap-structure shown, we make provision for cap-cooperation with the pen-equipped end of a fountain pen structure to afford protection to the pen, and additionally provide, in concealment within the cap, but for ready accessibility when needed, reservoir spaces for the reception of spare leads for the pencil structure, and an eraser; and with this construction we preferably make provision for effective retention of a holding clip exteriorly mounted on the cap. A further object of our invention is to provide a construction that may easily and cheaply be manufactured and assembled, and whereof the parts that are subjected to wear or deterioration may easily be replaced and which when in use in connection with either end structure of the combined instrument, does not interfere with proper balance or facile handling of the device.

To these ends, and the attainment of other objects which will become apparent to those skilled in the art from the following description, our invention consists in the features of construction and arrangements of parts hereinafter set forth and claimed.

In the drawings Fig. 1 shows a combined fountain-pen and lead pencil equipped with a cap embodying our invention, parts of the construction being broken away, the position of the cap when the fountain pen end of the instrument is in use being indicated by dotted lines; Fig. 2 is a vertical section through the cap structure; Fig. 3 is a horizontal section on line 3—3 of Fig. 2.

In the drawings 10 indicates a barrel,

with either end of which the cap 12 may 55 cooperate, said barrel having at one end a pen-point 13 and at its other end a pen pencil mechanism 14, of suitable renewable-lead construction. The barrel 10 may have near its pen-equipped end a screw-threaded 60 portion 13^a for cooperation with the cap, and near its pencil-equipped end a taper portion 14^a on which the cap may be frictionally seated by direct thrust. The cap 12 is formed with a rubber shell 41 open at 65 both ends, the lower end having internal provision of screw-threads 413 to engage the threads 13^a of the fountain pen barrel, and below such threads 413 a taper portion 414 for engaging the taper portion 14^a of 70 the barrel 10. Within the shell 41 a shoulder 43 is formed, beyond the range of interference with the tapered tip mechanism of the lead pencil, and preferably in position to coact with the pen-equipped end of the 75 barrel 10 for sealing purposes, and space above said shoulder 43 is utilized as follows:

An inner sleeve 44, preferably of rubber, is inserted into the upper open end of the cap 12 to make contact with the upper surface of the shoulder 43 and to leave a lead-receptive space between the sleeve and the cap wall, such space being preferably divided into compartments by ribs 45 on the exterior of the sleeve as best shown in Fig. 80 85 3. The sleeve length should be slightly greater than that of a replacement lead for the pencil mechanism, and in the open end of the sleeve a collar 47 is inserted, having a flange 48 partly to overlie the lead-receptive spaces 46. An eraser 49, of rubber or the like, is preferably carried in this flanged collar, the eraser shown being of mushroom shape, with a stem portion extending into the collar and a broad head 95 neatly overlying the collar-flange, so as to give an ample erasing surface and one that, adjacent its marginal edges, is firmly supported by the collar flange. The rubber sleeve 44 may have its ribs tightly fitted into 100 the cap body against accidental displacement, but the eraser-carrying collar should be readily removable from said sleeve to give free access to the lead 7 in the reservoir-compartment. A thin metal cap 50, slip-fitted on a slightly reduced portion 50' of 105 the rubber shell covers the eraser and gives an ornamental finish to the cap, but is readily

removable to give access to the internal parts.

A holding clip 51 is preferably provided, preferably taking form as a ball-ended 6 spring 52 formed between its ends into a suitable spring-bow 53 and having its narrow end 54 passed through an aperture in the side of the cap, and thence extended as at 55 along the inside of the cap in a groove 10 56 formed to receive it in one of the ribs 45 of the magazine-sleeve. By snugly fitting the spring-portion 55 in such a groove of ribs 45, the parts serve mutually to anchor each other and the spring clip is given a 15 very strong and effective bearing without the use of rivets or other usual fastening devices.

While we have herein shown and described a single embodiment of our invention in simple, compact form particularly designed for operative excellence and manufacturing economy, it will be apparent that changes in detail may be made without departure from the spirit of our invention within the 25 scope of the appended claims.

We claim:

1. A cap for a writing instrument of the character described, having an external wall, a sleeve interiorly spaced from said wall to provide renewal-lead spaces, a removable collar having a flange for partly overlying said spaces, and an end closure for the cap.
2. A cap structure of the character described having, in its normally-closed end portion, separated inner and outer walls affording a replacement-lead space, an

eraser holder detachably engaging the inner wall and partly covering the end of said renewal lead space, an eraser in said holder, and a detachable covering for said eraser 40 engaging, and normally closing the end of, said cap.

3. In a cap structure of the character described, a shell having an internal shoulder between its ends, a ribbed sleeve within the 45 portion of said shell beyond said shoulder, to provide replacement-lead compartments, and means for closing, in part at least, the end of said compartments remote from said shoulder, said means comprising a part 50 detachably carried by said ribbed sleeve.

4. A structure as set forth in claim 3 combined with a cap or end piece slip-engaging the outer wall of the shell, substantially as described.

5. In a cap structure of the character described, an outer shell, a removable cap for one end of said shell, and an eraser structure within said shell normally concealed by the cap, said eraser structure comprising 60 a flanged sleeve and a mushroom-shaped eraser carried thereby.

6. A cap structure of the character described having a shell, a ribbed sleeve within the 65 said shell providing renewal-lead spaces, a holding clip having an end portion passing through said shell and engaged by one of the said ribs, and a closure for the lead-receptive spaces.

GEORGE HOFMANN.
